UNITED STATES PATENT OFFICE.

CHARLES S. BIRD, OF EAST WALPOLE, MASSACHUSETTS.

PAPER BOX.

940,667.

Specification of Letters Patent. Patented Nov. 23, 1909.

Original application filed May 25, 1908, Serial No. 434,872. Divided and this application filed May 13, 1909. Serial No. 495,668.

To all whom it may concern:

Be it known that I, CHARLES S. BIRD, a citizen of the United States, and a resident of East Walpole, in the county of Norfolk 5 and State of Massachusetts, have invented certain new and useful Improvements in Paper Boxes, of which the following is a specification, reference being had to the accompanying drawings, in which—

10 Figures 1 and 2 are plan views of pieces of strawboard, cardboard, or the like, out of which my improved box is constructed; Fig. 3 is a plan view, slightly on the perspective, showing the two parts illustrated 15 in Figs. 1 and 2, united together and in a flat or "knock down" position; Fig. 4 is a perspective view of the parts shown in Fig. 3 set up in rectangular form. Fig. 5 is a perspective view of the box with the parts 20 assembled in final position for use and having the binding strip affixed thereto, said figure showing the single longitudinal strip encircling the entire box.

Similar letters refer to similar parts 25 throughout the several views.

The present application is a division of my prior application, Serial No. 434,872, filed May 25th 1908 and embraces certain modifications and alternative forms of construction of the invention therein shown.

In the construction of folding paper boxes of substantially rectangular form, it has been my experience that the parts assembled together which go to make up the box 30 should preferably have a certain strutting action, that is to say, the parts should mutually combine each with the other in order to afford the requisite strength and rigidity to the box, where such boxes are composed, 35 as in my improved box herein described, of material that is easily cracked or broken. It is also necessary and essential that the various parts should be so combined as to be capable of being packed and shipped in a 40 flat or "knock down" condition so as to economize freight charges, and, at the same time, be capable of being set up in final position in a simple and efficient manner when such boxes are to be used by the consumer. 45 It is also of commercial advantage, when large numbers of boxes are to be made and sold, to economize, as far as possible, in the use of the constituent material, to the end 50 that the various parts comprising the box 55 shall be compactly contiguous to one an-

other, so that when the box is cut and scored from a rectangular sheet of strawboard, or cardboard, the waste therefrom is reduced to a minimum.

The object of my invention, therefore, among other things, is to accomplish these 60 desired advantages in the construction of folding paper boxes, and to this end I take two pieces of rectangular strawboard, or cardboard, such as are shown in Figs. 1 and 65 2, and cut and score same, as illustrated in the figures, the heavy double lines being the cuts, and the light triple lines being the scored parts.

Referring to Figs. 1 and 2, A and A' constitute the side pieces of my box, provided on either side with extension flaps E, G, E', G', respectively, which extension flaps are integral with their respective sides. At one end of A and A' respectively are the end 70 pieces B, B', integral with A and A' respectively, and having integral with themselves the extension flaps C and D, and C' and D' respectively. At the opposite end of A and A' are the binding flaps F, F', respectively, 75 which, when the box is assembled in position, are bent inwardly and are fastened or secured by eyelets, rivets, or by any other means, such as adhesive, the flap F being, when the box is assembled in position, af- 80 fixed to the end of the end piece B', while the flap F' is affixed to the end of the end piece B, as is clearly illustrated in Fig. 4. It will be observed that the flaps C, D, E, G, C', D', E', G', are each of substantially 85 the same length as their contiguous end or side pieces respectively, A, B, A', B', and the combined width of the flaps E, G, and E', G', is substantially the same as the width of the sides A and A' respectively. 95

Having now described the various parts of my improved box, they are now assembled by having the flap F bent substantially at right angles and inwardly and affixed or otherwise secured to the inner surface of 100 the end piece B', while the flap F' is bent substantially at right angles and inwardly and affixed or otherwise secured to the inner surface of the end piece B, as is shown in Fig. 4, where the parts are more clearly 105 shown than in Fig. 3, Fig. 3 representing my improved box when the same is in a flat or "knock down" condition ready for shipment.

In assembling the various parts of my box 110

in final position, the extension flaps C, C', D, D', are bent inwardly and at substantially right angles with the end pieces B, B', whereby they furnish a strutting support to 5 the sides A, A'. Then the extension flaps of the sides E, E', G, G', are bent inwardly at substantially right angles with the sides A, A', and inasmuch as their combined width is that of the length of the end pieces 10 B, B', their exterior edges will close against each other, so as to form a further strengthening, strutting support for the sides. In case such extension flaps should not meet and close against each other, or should overlap, the strutting action would be largely, if not wholly, lost, but such construction would still be within the scope of my invention. However it is obvious that increased 15 strength and rigidity are attained by employing the strutting action hereinbefore described. I then take a single strip of strong paper or cloth shown in Fig. 5 by H², and paste or otherwise secure same so as to encircle the entire box longitudinally, thus 20 closing and holding securely in position the extension flaps E, E', and G, G', as shown in Fig. 5, the flaps meeting and closing along the dotted line, as respects E, E', as appears in this figure. This strip H² affords a convenient and secure method of holding these 25 extension flaps of the sides in position, and, at the same time, when it is desired to open the box, it can be readily cut or torn away.

It will be observed that my box, as finally 30 assembled, by the correlation of the various parts, affords a simple, strong and efficient, as well as economically advantageous paper box, such as can be shipped in a flat or "knock down" condition, and readily set up 35 and secured in permanent position by simple and efficacious means for holding the various parts together.

What I claim as new and desire to secure by Letters Patent is the following, viz:—

40 1. A rectangular folding paper box comprising end and side pieces having extension flaps having their combined width substantially the same as the width of said side and end pieces, turned in extension flaps integral 45 with the sides and bent in and secured to their adjacent end pieces, and means adapted to hold the extension flaps of the sides in position so as to form the top and bottom of the box, substantially as described.

50 2. A rectangular folding paper box, comprising end and side pieces having extension

flaps having their combined width substantially the same as the width of said side and end pieces, turned in extension flaps integral with the sides and bent in and secured to 60 their adjacent end pieces, and a binding strip encircling the entire box adapted to hold the extension flaps of the sides in position so as to form the top and bottom of the box, substantially as described.

55 3. In a rectangular folding paper box, the combination of two rectangular side pieces and two rectangular end pieces, one end piece and one side piece being integral with each other and the four being secured to 70 each other, extension flaps adapted to fold inwardly at substantially right angles with said sides and said end pieces, and means adapted to hold the extension flaps of the sides in position so as to form the top and bottom of the 75 box, substantially as described.

4. In a rectangular folding paper box, the combination of two rectangular side pieces and two rectangular end pieces, one end 80 piece and one side piece being integral with each other and the four being secured to each other, extension flaps adapted to fold inwardly at substantially right angles with said sides and said end pieces, and a binding 85 strip encircling the entire box adapted to hold the extension flaps of the sides in position so as to form the top and bottom of the box, substantially as described.

5. In a rectangular folding paper box, the combination of the side piece A and end piece B integral with each other, and the side piece A' and the end piece B' likewise integral with each other, the sides A and A' having integral with themselves respectively 95 the extension flaps E and G and E' and G', such extension flaps being substantially one-half the width of the sides A, A', end flaps F, F', integral with A and A', adapted to be bent inwardly at substantially right angles 100 and secured to the ends of the end pieces B', B, respectively, a binding strip H² encircling the entire box, adapted to hold the extension flaps of the sides E, E', G, G', in position so as to form the top and bottom of 105 the box respectively, substantially as described.

CHARLES S. BIRD.
